UNITED STATES PATENT OFFICE.

FRANCIS J. PLYM, OF NILES, MICHIGAN.

STORE-FRONT CONSTRUCTION.

1,274,773.

Specification of Letters Patent.

Patented Aug. 6, 1918.

Application filed May 19, 1915. Serial No. 29,088.

To all whom it may concern:

Be it known that I, FRANCIS J. PLYM, a citizen of the United States, residing at Niles, in the county of Berrien, in the State 5 of Michigan, have invented a new and useful Improvement in Store-Front Constructions, of which the following is a specification.

This invention relates to store front constructions and more particularly to corner and division bars of the type in which the adjacent edges of panes of glass are yieldingly clamped between a face plate and is so designed that while it is sufficiently yielding where it engages the glass, it also possesses the required strength to withstand the strain incident to its use.

These features of advantage and capabilities will become apparent from the detailed description of the accompanying drawings, in which there is illustrated one form of a sash bar embodying the invention. Of course, the construction there shown is illustrative only, and is not to be 25 understood as defining the limits of the invention.

Figure 1 shows a cross-section of a bar embodying the invention when used as a division bar, and

30 Fig. 2 shows the same when utilized as a corner bar.

Fig. 3 is a perspective view of the face plate.

Figs. 4 and 5 a similar view of the back 35 plate and reinforcing bar respectively.

Referring to the drawings in detail:

The reinforcing bar 1, which is constructed preferably of steel or iron, is of a cylindrical form provided with a slotted opening 2, and is of such a length as the height of the window requires, so that it will reach from the bottom to the top thereof. The face plate 3 is constructed of sheet metal, for example, drawn copper, as is also true 40 with the back plate 4, both of which, like the reinforcing bar, preferably extend from the bottom to the top of the window, in which case they are provided with a plurality of openings to receive screws 6, which 45 screws pass through the slot in the reinforcing bar and out the opposite side of said bar, where they are at their inner ends provided with suitable nuts. By properly adjusting the nuts the parts may be adjusted 50 toward or from each other.

It will be noticed that the back plate is

provided with glass engaging flanges and is so formed as to present a semi-circular bearing surface against the reinforcing bar, as a result of which and the slotted reinforcing bar, the construction, while yieldingly holding the glass in place, is nevertheless of sufficient strength to withstand the undue strain incident to its use, and is quite capable of supporting the frame at the upper 60 side of the window.

Further, by providing for a semi-cylindrical shaped bearing surface between the reinforcing bar and back plate the extent which the glass engaging flanges overlap the 70 glass may be adjusted by means of the fact that the bearing surface of the reinforcing bar, when the nuts are tightened, forces or drives the glass engaging flanges outwardly, which is an appreciable advantage when the 75 glass is cut scant or where it has pulled away from the bar due to settling of the building or frost.

By providing the reinforcing bar with the slotted opening, the bar is to an appreciable extent adapted to provide for the absorption of forces when abnormal strains are imposed upon the glass engaging flanges of the back plate, for in such instances the longitudinal edges of the reinforcing bar 80 will be moved toward each other.

In the manufacture of these devices, the face and back plates 3 and 4 respectively, are usually made from hard drawn copper which possesses an appreciable amount of 90 resiliency, but is sufficiently rigid to cause the vertical edges of the reinforcing bars to move slightly toward each other before becoming disformed sufficiently to take a permanent set. In other words, when undue 95 pressure is imposed upon the glass the back plate will give slightly before affecting the slotted bar, but as the pressure increases, for example, when subject to abnormal strains such as imposed by high winds, it will cause 100 the edges of the slotted bars to move slightly toward each other before becoming disformed.

I claim:

1. In a store front bar, the combination 105 of a resilient cylindrical reinforcing member provided with a vertical slot extending from one end to the other, a back plate, a face plate and means passing through said slot for securing said parts together for 110 the purpose set forth.

2. In a store front bar, the combination

of a resilient cylindrical reinforcing member provided with a slot extending from one end to the other, a back plate provided with a semi-circular bearing surface in direct engagement with the reinforcing member on the inner side thereof, a face plate and means for securing said parts together for the purpose set forth.

In witness whereof, I hereunto subscribe my name to this specification in the presence 10 of two witnesses.

FRANCIS J. PLYM.
